TWYER.

March 31, 1836

John Shugert of the County of Alleghany, Penn.
Letters Patent.The Schedule referred to in these Letters Patent, and making
part of the same, containing a description in the words of the
said John Shugert himself, of his improvement in Black
smiths Poc-Horn.

Be it known that I, John Shugert of the County of Alleghany
and State of Pennsylvania have invented a new and useful im-
provement in the Blacksmiths Poc-Horn, and the following is
an exact description of the construction and operation of the
Poc-Horn, as improved by me. The Poc-Horn, which I have im-
proved, consists in a pipe of about ten or twelve inches in length,
the hole through which is about two inches in diameter at the
back, and whereat the bellows pipe is inserted and gradually de-
minishes to one inch at the other end next the fire. In the
centre of said pipe, there is an angle inclining upwards of from
twenty to forty-five degrees. In place of the collar usually
welded on at the end next the fire there is a plate ten inches
long and nine broad, about one inch from the centre of which
there is to be an angle of about ninety degrees, the broad part of
this angled plate is to have a riser on the face of it at the centre
one inch high and two inches along the plate. The thickness
of said plate to be about three fourths of an inch. The whole to be
made of wrought or cast iron. The pipe and plate is to be put
together, so that the straight part of the pipe and the lower
edge of the plate, will range in a parallel line. The hole thru
the plate for the blast to be in the centre of the riser on the plate,
and to be about three eighths of an inch from the angle. it may
be cast in one piece or put together by rivets &c &c. It being thus
prepared as to be set in the forge, the lower part of the pipe
and bottom edge of the plate, to be set level, and so deep that the
upper edge of the hole for the blast will be about two inches below

the general surface of the forge. The back wall to be built upon
the back end of the plate leaving a space between the hole of
the blast and the back wall of five inches. The bellows to be
hung and used as usual.

Reference to the drawing. 1 The pipe. 2 angle in
pips. 3 blast hole. 4 lower edge of plate.

The improvement claimed by the petitioner is the
angle in the pipe and plate by which it is made entirely fire
proof or indestructible.
